UNITED STATES PATENT OFFICE.

CHARLES MUNTER, OF NEW YORK, N. Y.

MATERNITY-CORSET.

1,345,620.

Specification of Letters Patent.

Patented July 6, 1920.

Application filed December 5, 1917. Serial No. 205,623.

To all whom it may concern:

Be it known that I, CHARLES MUNTER, a citizen of the United States, residing in the city of New York, borough of Manhattan, county and State of New York, have invented a certain new and useful Maternity-Corset, of which the following is a specification.

This invention is a maternity corset adapted to be worn during pregnancy, as 10 well as after childbirth.

Maternity corsets have heretofore been so constructed that they serve to press tightly against the abdomen and force the same in an upward and rearward direction 15 by the application of relatively great pressure directly upon the abdomen. This practice, while universally pursued by the corsetières, has always found considerable opposition with the medical profession, since 20 the application of great pressure against the abdomen of a woman bearing a child not only is extremely uncomfortable and painful at times to the wearer, but almost invariably forces the child into an abnormal 25 position, thereby seriously interfering with the proper formation or growth of the child, as well as with the respiration of the wearer.

It has been long believed by corsetières that the application of a relatively great 30 force against the abdomen in an upward and rearward direction is desirable, and this is the end generally sought for in maternity corsets as long employed. While the effects 35 of wearing such a corset are generally harmful, said deleterious effects are most pronounced in ill-fitting corsets which apply a strong rearward pressure without the accompanying upward pressure. The effect 40 of such a corset is to cause marked constriction of the generative organs, which has a tendency to force them downwardly, frequently to a marked degree, so that, at 45 times, even a distended condition occurs.

I have discovered, by extensive experiments and a study of the human body, that the transmission of great pressure against the abdomen is entirely unnecessary to bring about the results sought for, since these results can be accomplished in a natural way 50 and through the agency of the muscles and ligaments which nature has provided. My experiments have shown that, if the backbone or spine is maintained in proper position, the ligaments and muscles referred to 55 will serve, through the carrying out of their

intended functions, to bring about a natural condition and to properly support the abdomen and stomach in a correct manner. It is well known that the abdomen, stomach and associated organisms are, literally, 60 hung from the spine, so that, if the spine is maintained in proper position, the remaining parts of the body referred to will be caused to assume their correct, natural relation. As a matter of anatomy, it is well 65 known to the medical profession that marked distention of the abdomen during pregnancy is an abnormal condition, nature having provided, in the structure of the female, for development of the child 70 through a broadening across the hips. If the child is lying correctly, its growth will be compensated for by a broadening of the body through the hips, rather than by a marked distention of the abdomen. In 75 maternity corsets heretofore employed, the hips have been forced together, with the result that the child is forced into an abnormal position, bringing about marked protrusion of the abdomen. If the tight lacing of the 80 corset is carried to extremes, it is not uncommon for the child to be forced into a substantially inverted, vertical position, which generally causes extreme discomfort to the mother, is injurious to the health of 85 the child, and renders the birth abnormal and dangerous to both parties.

With the foregoing considerations in mind, the object of the present invention is to construct a maternity corset wherein excess pressure upon the abdomen, or on any other part of the body, is obviated, but, by the use of such corset, the spindle column is caused to partake of its natural curvature, thereby causing the body to naturally maintain the parts of the torso in correct relative positions, so that sagging of the parts referred to does not occur.

A further object of the invention is to provide a corset which will carry out the 100 foregoing object but will not unnecessarily bind any portion of the body, the same merely conforming to the natural curves thereof to maintain the spine at its proper curve, while readily compensating for such 105 hip expansion as is necessary to the well-being of the mother and child.

A further object which may be adverted to is the provision of a corset which may be readily and easily put on and adjusted 110

and which will distribute its tension and the natural expansion throughout the entire garment.

Features of the invention, other than those specified, as well as the advantages thereof, will be apparent from the herein-after detailed description taken in conjunction with the accompanying drawings.

In the accompanying drawings I have illustrated different practical embodiments of the invention, but the constructions therein shown are to be understood as illustrative, only, and not as defining the limits of the invention.

Figure 1 is a three-quarter front elevation of a maternity corset embodying the present invention in place upon a person.

Fig. 2 is a rear view of the structure of Fig. 1, and

Fig. 3 is a modified form of corset embodying the present invention laid out flat.

Referring to the drawings, and more particularly Figs. 1 and 2 thereof, A designates the corset. Said corset is of the front opening type and its meeting edges are provided with coöperating posts b and eyelets b', by means of which said meeting edges may be secured together, with the corset wrapped about the figure. The posts and eyelets are preferably rigidly secured to stays B and B', respectively, which are incorporated into the corset at the meeting edges thereof.

The corset is built up of a plurality of sections sewed together so as to properly shape the corset, particular attention being given to the shaping of the back thereof, as upon the shaping of the back depends the efficiency of the corset in the carrying out of its functions. The central back of the corset is preferably without openings, so that an unobstructed portion will overlie the spinal column and will impart the proper, natural curvature thereto, but, in order that the corset will properly conform to the contour of the body, the back portion thereof is provided with openings C, which extend upwardly from the lower edge of the corset to above the waistline. Similar openings D are provided at either side of the medial line of the front of the corset, which back and front openings C and D serve, collectively, to cause the garment to conform to hip dimensions, *i. e.*, the dimensions of the body at and below the waistline. While it is recommended that the central back of the garment be closed, as described, and the openings C be positioned at either side of the spinal column, a central opening may be provided after the manner shown in my prior Patent No. 848,479, March 26, 1907. The form of cross-lacing with belt shown in this patent may be employed, with a central opening in the back of the corset of this invention, without de-

parting from said invention. Moreover, the back of the corset may be provided with an opening J, extending downwardly from the upper edge thereof and closed by a lacing j of any desired form, but the best results are obtained if the central back is closed, and this is the structure preferred.

The front of the garment is also provided with openings E, which extend downwardly from the upper edge to or slightly below the waistline and are positioned in juxtaposed relation to the breasts. These upper openings E assist the lower openings C and D in the conformation of the garment to the figure at the waistline, and operate independently above the waistline to shape the upper portion of the garment to the figure and, more particularly, to produce the proper fit at the breasts.

While the said openings may be adjusted by the employment of any form of lacing desired, it is difficult for women, who, as a rule, are not familiar with mechanical or physiological principles, to properly adjust said openings by independent lacings. Accordingly, in the preferred embodiment of the invention, rear openings C are closed by one series of laces, while all of the front openings are closed by another series. In order that these lacings may be properly adjusted, they are preferably associated with belt portions so that the wearer is merely required to buckle a belt about the person in order to obtain proper adjustment of the back openings, and a second belt about the person in order to properly adjust the front openings. A very satisfactory arrangement is shown in Figs. 1 and 2, wherein the belt for closing the back openings is designated F. The belt is made in two sections and to the rear of each section are secured a number of tapes f which are passed through eyelets f' positioned in the central back portion and adjacent the edge of openings C, as best shown in Fig. 2. Tapes f are thence carried across the openings C and are secured, as at e, to the opposite edges of said openings. Laces f are of different lengths, and these lengths are so proportioned that, when belt F is drawn about the figure and secured at the front, as shown in Fig. 1, all of the laces will be placed under tension, and, as the belt is drawn tight, openings C will be closed to such extent that the central back portion of the corset will be drawn into the correct curvature of which the spinal column should normally partake. The proportioning of the lengths of laces f and the shaping of the central back portion are of great importance, since, through their agency, the vertical contour or curvature of the central back portion is determined, and this curvature, in turn, determines the position of the spinal column of the wearer.

The lacings shown and described for

closing back openings C, and those which will be hereinafter described for closing the front openings D and E, work out very well in practice, but, if desired, other forms of 6 lacing may be employed. For example, the form of double lacing shown in my application for patent on "Lacing" filed herewith, Serial No. 205,622, wherein each lace passes twice across the opening which it closes before being secured to the belt, may be used. 10 In fact, any form of belt-operated lacing may be employed to close openings C, D and E, and any other form of independent lacing may be employed to close opening J, such, for example, as shown in my other 15 application for "Lacing" filed herewith.

The lower front openings D are closed by lacings *g* secured to one edge *d* of each lower front opening, pass through eyelets *g'* at the 20 opposite edge thereof, and thence pass and are secured to the opposite ends of belt G. To said opposite ends of belt G are also secured the laces *h*, by which openings E are 25 adjusted, said laces *h* coöperating with the upper openings E in the same manner as described with reference to the lower openings. In the same manner as the tightening of belt F serves to adjust the back openings C, the tightening of belt G serves to 30 adjust the front openings D and E. In the same manner does belt G exert its greatest force in the vicinity of the waistline and a lesser force in the lower portion of the garment and about the breasts.

35 In the construction of Fig. 3, which shows a modified form of the invention, the corset is constituted the same as hereinbefore described with reference to the embodiment of Figs. 1 and 2, but, instead of providing 40 a separate belt G for the front lacings of the garment, the structure of Fig. 3 contemplates the simultaneous adjustment of all of the lacings by a common belt F'. In this construction, the lacings are so proportioned that, when belt F' is drawn tightly 45 about the wearer, all of the lacings will be automatically and simultaneously adjusted to properly shape the garment to the figure. This construction has some advantages over 50 the construction of Figs. 1 and 2, primarily in the fact that one set of lacings cannot be made tighter than another, and secondarily in the ease of adjustment through the manipulation of a single belt. Both forms 55 of corset described may be provided with hose supporters H, depending from the lower edge thereof, but these hose supporters may or may not be embodied, as desired.

60 From the foregoing description of both forms of the invention, it will appear that their modes of operation are the same. By the tightening of the belt or belts, the central back portion of the corset is caused to 65 assume the proper curvature and to this

curvature the spine conforms, so that the shoulders are thrown well back and the small of the back hollowed to the desired extent. The body is held erect without undue pressure on the abdomen, and, by holding the body erect and maintaining the proper curvature of the spine, the muscles and cords of the abdominal wall and interior organs are pulled taut and serve to support or suspend the parts with which 70 they are associated in a natural manner directly from the backbone. The abdominal wall is thus sustained by the forces of nature and not by an exteriorly applied pressure, as was depended upon in prior corsets. 75

The corset of this invention is not restricted to use during pregnancy, but is equally well adapted for continued use after the birth of the child, as it continues to maintain the spine in proper position and, in so 80 doing, not only renders the system more healthy, but, also, allows the parts of the body to return to their normal positions, this being accomplished naturally by the muscular tissues of the body in a healthy 85 manner and in the absence of deleterious and painful pressures which would serve to render the recovery more slow and less sure.

In the carrying out of this invention, it will, of course, be understood that the corset is properly reinforced by suitable stays so disposed as to render the conformation of the garment to the wearer most complete and satisfactory. Several of these stays are shown in the drawings in dotted lines and 90 are designated by the reference character *i*. The disposition of the stays may, however, be varied from that shown without departing from the spirit of the invention. Other slight modifications may be made entirely 95 within the scope of this invention, and it is, therefore, to be understood that the same is not limited to the specific structure shown and described, but is as broadly novel as is 100 commensurate with the appended claims. 105

Having thus fully described the invention, what I claim as new, and desire to secure by Letters Patent, is:

1. A maternity corset embodying a body portion provided in the front thereof, on either side of the medial line of said front, with an upwardly extending opening and a downwardly extending opening, lacings coöperating with each of said upwardly and downwardly extending openings, a belt common to all of said lacings for adjusting the openings, two upwardly extending openings in the back of the garment, each of which is positioned laterally of the medial line of the back, lacings associated with each of said openings and a belt coöperating with the lacings for adjusting the size of said openings. 115

2. A maternity corset having a body portion provided in the front thereof, on either 120

side of the medial line of said front, with an upwardly extending opening and a downwardly extending opening, lacings coöperating with each of said upwardly and downwardly extending openings, a belt common to all of said lacings for adjusting the openings, two upwardly extending openings in the back of the garment each of which is positioned laterally of the medial line of the back, lacings associated with each of said openings, and a belt coöperating with the lacings for adjusting the size of said back openings, in combination with additional lacing associated with an opening in the medial line of the back of the corset.

3. A maternity corset having a body portion provided in the front thereof and at either side of the medial line of the front with openings extending upwardly from the lower edge to a point above the waist line of the wearer, and having an additional pair of openings positioned one on either side of the medial line of the front and extending downwardly from the upper edge of the corset to points below the upper ends of the upwardly extending openings, belt operated lacings associated with each of the openings in the front of the corset, and said body portion being provided with a further opening in the back of the corset, and lacings for adjusting the size of said further opening.

4. A maternity corset having a body portion provided in the front thereof and at either side of the medial line of the front with openings extending upwardly from the lower edge to a point above the waist line of the wearer, and having an additional pair of openings positioned one on either side of the medial line of the front and extending downwardly from the upper edge of the corset to points below the upper ends of the upwardly extending openings, belt operated lacings associated with each of the openings in the front of the corset, said body portion being further provided with two upwardly extending openings in the back of the corset one of which is positioned on each side of the medial line of the back of the garment, and belt operated lacings associated with each of said back openings.

5. A maternity corset having a body portion provided with openings two of which are positioned in the front of the garment on either side of the medial line thereof and extend upwardly from the lower edge of the garment, two other of which are positioned on either side of the medial line of the front and extend downwardly from the upper edge to points below the upper ends of the two

other front openings, and two other of which openings are positioned in the back of the garment, one on either side of the medial line of the back of the garment, and belt operated lacings associated with each of said openings.

6. A maternity corset having a body portion provided with a plurality of openings, two of which are positioned in the front of the garment and extend upwardly from the lower edge thereof and two other of which are positioned in the front of the garment and extend downwardly from the upper edge thereof to points below the upper ends of the other two front openings, and belt operated lacings associated with said openings.

7. A maternity corset having a body portion provided with a plurality of openings, two of which are positioned in the front of the garment and extend upwardly from the lower edge thereof and two other of which are positioned in the front of the garment and extend downwardly from the upper edge thereof to points below the upper ends of the other two front openings, and belt operated lacings associated with said openings, in combination with additional lacing co-operating with an opening in the back of the corset.

8. A maternity corset having a body portion provided with a plurality of openings, two of which are positioned in the front of the garment, one on either side of the medial line in the front and extend upwardly from the lower edge of the garment to points above the waist line, two other of which are positioned in the front of the garment, one on either side of the medial line of the front and extend downwardly from the upper edge of the garment to substantially the waist line, and two openings of which are positioned in the back of the garment, one on either side of the medial line of the back extending upwardly from the lower edge of the garment to a point above the waist line, and belt operated lacings associated with all of the openings.

9. A maternity corset having a body portion provided in the front thereof with a plurality of openings extending upwardly from the lower edge of the opening and downwardly from the upper edge thereof, and belt operated lacings associated with said openings.

In testimony whereof I have signed my name to this specification.

CHARLES MUNTER.
